(57) **CLAIM**

The ornamental design for a sprinkler body, as shown and described.

DESCRIPTION

FIG. 1 is a perspective view of a portion of a sprinkler body;

FIG. 2 is a top plan view thereof;

FIG. 3 is a front view thereof (the back view being identical to the front view); and,

FIG. 4 is a right side view thereof (the left side view being identical to the right side).

The lines shown in phantom are for illustrative purposes only and do not form part of the invention.
